DESIGN FOR A DRINKING GLASS

John W. Brown, Cleveland, Ohio

Application May 19, 1939, Serial No. 85,088

Term of patent 7 years

To all whom it may concern:

Be it known that I, John W. Brown, a citizen of the United States of America, residing in the city of Cleveland, county of Cuyahoga, and State of Ohio, have invented a new, original, and ornamental Design for a Drinking Glass, of which the following is a specification, reference being had to the accompanying drawing, forming part thereof.

In the drawing:

Fig. 1 is a front perspective view of a drinking glass showing my design; and

Fig. 2 is a rear perspective view of Fig. 1.
The hatching represents bands and fields of contrasting color.

I claim:

The ornamental design for a drinking glass, as shown and described.

JOHN W. BROWN.
